UNITED STATES PATENT OFFICE.

EDGAR W. CLEVELAND, OF GRAND RAPIDS, MICHIGAN.

VARIABLE-SPEED GEARING.

1,121,000.

Specification of Letters Patent. Patented Dec. 15, 1914.

Application filed August 29, 1913. Serial No. 787,288.

To all whom it may concern:

Be it known that I, EDGAR W. CLEVELAND, a citizen of the United States of America, residing at Grand Rapids in the county of 5 Kent and State of Michigan, have invented certain new and useful Improvements in Variable-Speed Gearing; and I do hereby declare the following to be a full, clear, and exact description of the invention, such as 10 will enable others skilled in the art to which it appertains to make and use the same.

My invention relates to improvements in variable speed gearing and particularly adapted for multiple spindle drills, and its 15 object is to provide a device in which the separate spindles may be rotated at different speeds; in which any or all of the spindles may remain idle while the driving member rotates; to provide a device simple and 20 compact in construction, and to provide the same with various novel features of construction and arrangement as hereinafter more fully described and particularly pointed out in the claims.

25 It is often desirable in multiple spindle drills to rotate the various spindles at different speeds, as for instance, when drills of different sizes are used, and it often occurs that all of the spindles are not used 30 and it is desirable to allow certain spindles to remain idle while the others rotate. I accomplish these desirable objects in the form of my invention shown by a series of main driving gears rotated at different speeds by 35 a common driving shaft, and each spindle shaft is provided with a longitudinally movable pinion adapted to mesh separately with any one of said gears or to be moved and retained between the gears in inoperative position.

40 This invention also embodies various novel and useful features, as will more fully appear by reference to the accompanying drawings, which illustrate the preferred 45 construction and arrangement of a device embodying my invention, in which drawings:

Figure 1 is a vertical section through the 50 axis of the head of a device embodying my invention; Fig. 2 is a sectional plan on the line 2—2 of Fig. 1; Fig. 3 is a detail view of a portion of the head illustrating the means for moving the sleeves to which the 55 slidable pinions are attached; and Fig. 4 is a horizontal section on the line 4—4 of Fig. 3.

Like numbers refer to like parts in all of the figures.

1 is the head of a multiple spindle drilling machine, preferably cylindrical in shape and attached in the usual way to the frame of the machine. A main driving shaft 2 is journaled in the axis of said head, its upper end projecting therefrom and provided with a driving pulley 3, to which it is keyed as at 4. The hub 5 of the said pulley extends into a boss 1^a on the head and is journaled therein, thus supporting the upper end of the shaft 2. The lower end of said shaft is provided with an axial opening to receive a stud 6, which is integral with a pedestal 7 attached to the lower end of the head 1 and projecting upward in the axis thereof. This stud 6 forms a bearing for the lower end of the shaft 2. The shaft 2 has keyed to its lower end a driving gear 8 which constitutes the positive or direct driving gear of the series. A sleeve 9 surrounds the shaft 2 and is retained non-rotative by means of a pin 10 at its upper end and is provided at its lower end with a gear 11, 80 preferably formed integral therewith. A gear 12 provided with both external and internal teeth surrounds the stationary gear 11 and is spaced away from the same and is attached to the lower end of a hub 13 85 which surrounds the sleeve 9 and rotates thereon. Pinions 14 are journaled on studs 15 mounted upon the main driving gear 8 and these pinions mesh both with the stationary gear 11 and with the internal teeth 90 of the rotating gear 12. This train of gears constitutes a planetary gear system deriving its power from the main gear 8 and driving the gear 12 at a greater velocity than the main gear. A fixed gear 16 is provided on 95 the pedestal 7 and a gear 17 having internal and external teeth surrounds the said fixed gear 16 and its hub 18 rotates upon the said pedestal 7. Pinions 19 are interposed between the gear 16 and the internal teeth 100 of the gear 17, and these pinions are journaled on studs 15 mounted on the main driving gear 8. This train of gears constitutes a second planetary gear system obtaining its power from the gear 8 and driving the 105 gear 17 at a higher velocity than said gear 8. The ratios of these two planetary gear systems differ, so that the speed of rotation of each of the gears 8, 12 and 17 is different. It will be noted, however, that the outer 110

pitch diameter of each of these gears is the same.

Surrounding the gears 8, 12 and 17 are a series of vertical shafts 20 journaled in the head and having their lower ends projecting therethrough and each connected by universal joints 21 to a shaft 22, to drive the drill spindles (not shown). Upon each shaft 20 a pinion 23 is splined by means of a sliding key 24, and each of these gears is adapted to be shifted longitudinally upon the shaft into mesh with either of the driving gears 8, 12 and 17, or it may be adjusted in any space between the said gears and out of engagement therewith, and thus the pinion, together with its shaft, will remain idle.

Each shaft is surrounded above the pinion by a sleeve 25 and the key 24 is slidable in a way in the shaft and has at its upper end an outward projection 24^a which traverses an annular groove on the interior of said sleeve. The lower end of the key is provided with a similar outward projection which engages the underside of the pinion, and thus the pinion is rotatably connected to the sleeve 25. Each sleeve 25 is provided on its outer surface with a series of annular grooves 26 so spaced that each will be successively engaged by a spring actuated ball 27 located in the head 1 for the purpose of retaining the pinion 23 in any one of the positions where it will properly mesh with the desired gear or in either of its disengaged positions.

The sleeves 25 always project through the upper end of the head 1 and may be grasped by any convenient tool to be moved to the desired position. Figs. 3 and 4 illustrate a desirable tool for this purpose, which consists of a lever 28 having a fulcrum 29 and a bifurcated end 30 adapted to embrace the sleeve and provided with projections 31 to enter the annular grooves 26 therein. It is obvious that by placing this lever in the position illustrated in Fig. 3 with the projections 31 within an annular groove in the sleeve 25, that depressing the outer end of the lever will pry the sleeve upward a distance equal to the space between two of the annular grooves. By repeating this operation the sleeve may be raised to the desired position, and by engaging the lever with the pulley the sleeve may be lowered.

It will be seen that in the above described mechanism I have provided three superimposed driving gears rotating about a common axis, each with the same pitch diameter, but each having different speeds of rotation. This enables the drill spindle driving shafts to be grouped as closely as desired about the said driving gears and the movement from any one of said gears to be transmitted through the slidable pinion 23 to its respective shaft.

The construction of the device is simple,

as is also its operation. Furthermore, the gearing is compact, occupying very little space and not requiring a large unsightly gear casing, and owing to the peculiar arrangement of the gears, the whole device 70 may be constructed substantial and strong.

What I claim is:

1. Variable speed gearing comprising a main driving shaft, a plurality of superimposed driving gears in axial alinement and having the same pitch diameter, means for rotating said gears at different speeds actuated by said driving shaft, a shaft arranged near said driving gears, a pinion splined to said shaft, and means for separately moving said pinion into mesh with either one of said driving gears. 75

2. Variable speed gearing comprising a main driving shaft, a main driving gear fixed thereto, variable speed driving gears of the same pitch diameter as the main gear and arranged in axial alinement with the same, planetary gears to drive said variable speed gears from the main shaft and at different speeds, a shaft arranged near said driving 90 gears, a pinion splined to said shaft, and means for moving the said pinion into mesh with either one of said driving gears.

3. Variable speed gearing comprising a main driving shaft, a main driving gear fixed thereto, a fixed gear surrounding said shaft above the main gear, a ring gear having inner and outer teeth surrounding said fixed gear and spaced away from the same, pinions carried by the main gear and meshing with both the fixed gear and the interior teeth on the ring gear, a shaft arranged near the main and ring gears, a pinion splined to said shaft, and means for moving said pinion into mesh with either the ring gear or 100 the main gear. 105

4. Variable speed gearing comprising a main driving shaft, a main gear fixed to said shaft, two fixed gears located above and below said main gear and in axial alinement therewith, said fixed gears being of different diameters, a ring gear having internal and external teeth surrounding each of said fixed gears and spaced away therefrom, planetary pinions carried by the main gear and connecting the fixed gears and the ring gears, a shaft arranged near said gears, a pinion splined to said shaft, and means for moving the pinion into mesh with either said main gear or either ring gear. 110 115

5. Variable speed gearing comprising a gear case, a main driving shaft axially journaled in said gear case, a plurality of driving gears having the same diameter within said case, means for rotating said gears at different speeds by means of said shaft, a shaft arranged near the peripheries of said driving gears, a pinion splined to said shaft and adapted to mesh with any one of the driving gears, a sleeve surrounding the 120 125

shaft and rotatably connected to the pinion thereon and also having one end projecting through said gear case, and means for adjusting said sleeve longitudinally of the respective shaft.

6. Variable speed gearing comprising a gear case, a main driving shaft journaled in said case, a plurality of driving gears having the same diameter arranged within said 10 case and in axial alinement with each other, means for rotating said gears at different speeds operated by said shaft, a shaft arranged adjacent the peripheries of said gears and also having a longitudinal key- 15 way, a pinion surrounding said shaft, a key slidable in the said keyways, said key hav-

ing an outward projection at its lower end to engage the pinion, and a similar outward projection at its upper end, a sleeve surrounding said shaft and having an interior 20 annular groove to receive the upper projection on the key said sleeve also extending outside of the gear case, and means for adjusting said sleeve and pinion in any one of several positions.

In testimony whereof I affix my signature in presence of two witnesses.

EDGAR W. CLEVELAND.
